CLAIM

The ornamental design for a support for electronic device protector, as shown and described.

DESCRIPTION

FIG. 1 is rear perspective view of our support design for an electronic device protector shown with the protector in closed position and the support deployed. The protector is shown in broken line and is included for merely illustration purposes to show the support design in its environment and forms no part of the support design claim.

FIG. 2 is a left side view of the support design of FIG. 1.

FIG. 3 is a right side view of the support design of FIG. 1; and, FIG. 4 is a rear view of the support design of FIG. 1.

The support design is not visible from the front, top, or bottom view of the protector.
